UNITED STATES PATENT OFFICE

91,469

DESIGN FOR A RADIOCABINET

Joseph L. Raffetto, New York, N. Y.

Application November 25, 1933. Serial No. 49,862

Term of patent 7 years

To all whom it may concern:

Be it known that I, JOSEPH L. RAFFETTO, a citizen of the United States of America, residing at New York City, county and State of New York, have invented a new, original, and ornamental Design for a Radiocabinet, of which the following is a specification, reference being had to the accompanying drawing forming part thereof.

Figure 1 is a side view of a radiocabinet showing my new design.

Figure 2 is a front view of the radiocabinet shown in Figure 1.

Figure 3 is a rear view of the radiocabinet shown in Figure 1.

I claim:

The ornamental design for a radiocabinet as shown.

JOSEPH L. RAFFETTO.
